UNITED STATES PATENT OFFICE.

ALFRED WALKER EMPSON, OF LONDON, ENGLAND.

WATER-HEATER.

1,367,502.

Specification of Letters Patent.

Patented Feb. 1, 1921.

Application filed September 17, 1920. Serial No. 411,019.

To all whom it may concern:

Be it known that I, ALFRED WALKER EMPSON, a subject of the King of Great Britain and Ireland, and residing at 17 5 Boscombe road, London, W. 12, England, have invented certain new and useful Improvements in Water-Heaters of which the following is a specification.

This invention relates to heaters or boilers of the kind adapted for raising the temperature of water or other liquids, in contradistinction to pressure steam generators.

The object of the invention is to provide an improved heater or boiler which can be 15 built quickly and cheaply and in which liquid can be heated with greater rapidity and more economically than in water heaters as previously proposed.

According to the present invention the 20 heater or boiler comprises in combination a casing inclosing a water tubular boiler, a vertically adjustable frame supporting fire bars arranged beneath the boiler and a pivoted flap forming the rear wall of the grate 25 and adapted to be angularly adjusted in conjunction with the vertical adjustments of the fire bars for the purpose of varying simultaneously the vertical and longitudinal dimensions of the grate.

30 In the accompanying drawings, which illustrate a water heater constructed in accordance with the present invention:—

Figure 1 is a side elevation partially in section, and

35 Fig. 2 is an end view, the right-hand half being a section taken on the line 2—2 of Fig. 1.

In the illustrated embodiment of the invention the liquid is heated in a tubular non-pressure heater or boiler comprising a bank 40 of inclined water tubes *a* which are expanded or otherwise secured at their ends into headers or boxes *b* and *c* of rectangular or other form. The headers *b* and *c* communicate with a receiver tank *d* by means of pipes or conduits *e* and *f* respectively, whereby the water, when heated, circulates by thermo-siphonic action in a closed circuit, the path of which is indicated generally by the arrows in Fig. 1. The upper header *b* is provided with a detachable cover *g* so that it is possible to cleanse this header and the water tubes when desired. The lower header *c* is provided with a mud-hole *h* and a drain pipe *i*, the latter being 50 provided with a suitable plug or cock. The receiver tank *d* has an inlet pipe *j* by means of which the tank can be refilled or kept charged with liquid, usually water. An off-take pipe *k* having a suitable controlling valve is also provided on the tank *d*, preferably being located, as illustrated, toward that end at which the heated water passes up into the tank, and spaced a short distance above the bottom of the tank so that it is 55 impossible to draw off the whole of the water in the event of a failure of the supply.

The parts hereinbefore described are inclosed in a suitable casing or chamber *l* illustrated as being rectangular in shape. 60 The chamber *l* is lined with refractory material *m*. The tank *d* is secured in position at the top of the casing *l* by suitable means such as T-iron supports *n* carried by brackets or other means on the lateral walls of the 65 casing. The upper header *b* rests on a T-iron support *o* embedded in a shoulder *p* of the refractory lining, and a block *q* is provided on the bottom wall of the casing to support the lower header *c*. Baffle plates 70 *r* and *s* are arranged at intervals along the tubes to cause the hot gases from the furnace to take a circuitous path around and over the tubes, so as to utilize as much as possible of their heat before they escape 75 by way of the flue or chimney stack *t*.

The fire bars *u* are mounted on a rectangular frame *v* and, according to the present invention, provision is made for raising or lowering them, for the purpose of varying 80 the capacity of the furnace chamber, according to the nature of the fuel which is to be burnt in the grate. A larger grate area and deeper fire is necessary to insure the economical combustion of bulky fuel, 85 such as wood, than is the case for less bulky fuel, as coal or coke. The bars may be raised or lowered by any convenient mechanism, the example shown comprising two pairs of forked links *w* pivoted one to each 90 side limb of the frame *v*. The lower ends of the links on either side are pivotally connected to nuts *x* working on a screw-threaded spindle *y* mounted in bearings *z* in the side wall of the casing. One link works 95 on a right-handed thread 3 and the other on a left-handed thread 4, so that rotation of the spindle *y* causes the nuts *x* to move toward or away from each other and, through the medium of the links *w*, these 100 movements will cause the frame *v* and bars carried thereby to be elevated or depressed.

Bevel wheels 5 are provided on the spindles *y* which are rotated simultaneously by means of bevel wheels 6 mounted on a transverse spindle 7. This spindle is mounted in suitable bearings in the casing and is provided exteriorly of the latter at each extremity with an operating handle or crank 8.

Provision is also made whereby the length 10 of the fuel space can be varied. This is effected by means of a wall or flap 9 pivoted on a horizontal, transverse rod 10, and faced with refractory material 11 on the sides exposed to the burning fuel. The rod 15 10 passes through bearings in the side walls of the casing and is provided at its ends with operating handles 12 for effecting the angular adjustment of the flap. Since the handles 8 and 12 are provided on both sides 20 of the casing and in close proximity to each other the adjustment of the bars and of the flap can be effected by one person simultaneously at either side of the casing. In this connection it is to be understood that 25 any suitable mechanism may be employed for effecting the adjustments of the bars and flap.

Fig. 1 shows the grate arranged for burning coal or coke, the bars being in their 30 highest position and the flap in its foremost position and therefore providing the minimum grate capacity. When it is desired to have the maximum space for fuel, the bars are manipulated down to their lowest 35 and the flap to its rearmost position. The rear position of the flap is indicated in dotted lines, and in this position the rounded free end of the flap bears against a horizontal block 13 of refractory material. In 40 the rear position also the flap lies adjacent and parallel to a wall 14 extending between the baffle plate *r* and the bottom wall of the casing, and in effect forming an extension of the baffle *r*.

Immediately above the receiver tank *d* is 45 a platform or chamber 15 which may have a hinged or other lid or lids 16. Cans of lubricating oil or other vessels or material to be heated are placed within the chamber 15 and are warmed by the heat radiating 50 from the upper wall of the tank *d*. An outlet aperture or pipe 17 may be provided at the top of the tank *d* to allow any steam which may be generated in the boiler to pass 55 from the tank *d* into the chamber 15 to assist in further heating the vessels contained therein. A drain outlet or pipe 18 leading from the bottom of the chamber 15 allows for the escape of water formed by the condensation of steam, together with 60 any leakage of oil from the cans.

The whole is supported on a suitable base which may be supported by land or road wheels 19, or on a motor chassis, to render the heater easily transportable.

Either natural or mechanically forced draft may be employed as is the more convenient.

Having now described my invention, what I claim as new and desire to secure by Letters Patent is:—

A water heater comprising a casing, a boiler mounted in said casing, a vertically adjustable grate mounted in said casing below said boiler, a flap having its upper end 75 pivotally mounted above the grate and its lower end engaging said grate, said grate normally locking the flap against movement in one direction, and means for moving the pivoted flap after the grate has been adjusted.

In testimony whereof I have signed my name to this specification.

ALFRED WALKER EMPSON.
